UNITED STATES PATENT OFFICE.

RAYMOND P. JACOBS AND STANLEY M. WINARSKI, OF STEVENS POINT, WISCONSIN.

MOTORIST'S GOGGLES.

Application filed May 21, 1923. Serial No. 640,576.

To all whom it may concern:

Be it known that we, RAYMOND P. JACOBS and STANLEY M. WINARSKI, citizens of the United States, residing at Stevens Point, in 5 the county of Portage and State of Wisconsin, have invented certain new and useful Improvements in Motorists' Goggles; and we do declare the following to be a full, clear, and exact description of the invention, 10 such as will enable others skilled in the art to which it appertains to make and use the same.

Our invention relates to improvements in eye shields or goggles to prevent the blinding of motorists by approaching headlights and the object of the invention is to provide an extremely simple and inexpensive, yet an efficient and easily operated device for obtaining the desired results.

20 With the foregoing in view, the invention resides in the novel subject matter herein-after described and claimed, the description being supplemented by the accompanying drawing.

25 Figure 1 is a front elevation of an eye shield constructed in accordance with our invention.

Figure 2 is a vertical transverse sectional view on line 2—2 of Fig. 1.

30 Figure 3 is an elevation showing a different form of construction.

Figure 4 is a transverse sectional view on line 4—4 of Fig. 3.

35 In the form of construction selected for illustration in the present application, we provide a pair of open frames 1 connected by a nose bridge 2 for disposition in front of the user's eyes, any suitable means such as the usual side wires or temples 3, being employed for securing the frames and bridge in place.

40 Extending forwardly from each of the frames 1 is a shield 4 which extends throughout approximately half the circumference of the frames and is located either above or below a horizontal plane intersecting the frame axis. The front ends of the shields 4 terminate in a common vertical plane at substantially right angles to the aforementioned 45 axis and we have shown the front corners of each of said shields connected by a horizontal bar 5.

45 Carried by the front end of each shield 4, is a pair of horizontally spaced vertically disposed panels 6 formed of any desired

light intercepting material, which may be opaque or translucent as desired. The panels 6 are disposed at opposite sides of the line of vision or axis of the user's eye when looking straight ahead, providing an appreciable 50 view opening 7 between them.

The panels 6 may be secured in place in any desired manner, but we prefer to bend the front ends of the shields 4 into channel-shaped formation as indicated at 8 and to 55 similarly bend the bars 5, the edges of the panels being held in the channels.

By employing the construction shown, it will be seen that when glaring headlights approach, the user of the invention need only 60 turn his head slightly to cause certain of the panels 6 to cast shadows upon the pupils of his eyes, thus shielding them and permitting clear vision through the openings 7.

If desired, the frames 1 may be provided 65 with guides 9 on their inner ends to adjustably receive extensions 10 on the ends of the nose bridge 2, set screws or the like 11 being provided to hold said guides and extensions in adjusted position. This arrangement will 70 permit adjustment of the frames toward and from each other, according to the distance between the user's eyes.

As excellent results have been obtained 75 from the details disclosed, these details may be followed if desired, but it is to be understood that within the scope of the invention as claimed, numerous changes in form, proportion and details, may be made. For instance, the panels 6 need not be in truly vertical planes, but may incline if desired. Furthermore, they may be slightly oblique 80 to the eye axes when viewed from above, if found desirable.

We claim:

1. An eye-shield comprising a pair of open frames connected by a nose bridge, curved shields extending forwardly from said frames and disposed below a medial horizontal plane, the front ends of said shields terminating in a substantially vertical plane at substantially right angles to the axes of the frames, and a pair of light intercepting panels carried by the front end of each of said shields, each pair of said panels being spaced apart horizontally and disposed at opposite sides of the above-named axes to provide an unobstructed clear vision field between them and having their upper edges terminating on a horizontal line transverse to and substan- 95 100 105 110

tially intersecting said axes, leaving an entirely unobstructed clear vision field above said panels.

2. A structure as specified in claim 1; together with a pair of horizontal bars connecting the front corners of said shields and assisting in holding said panels.

3. A structure as specified in claim 1; the front ends of said shields having inwardly

opening channels receiving edge portions of 10 said panels, and a pair of horizontal bars connecting the front corners of said shields and also having channels which receive the upper edges of said panels.

In testimony whereof we have hereunto affixed our signatures.

RAYMOND P. JACOBS.
STANLEY M. WINARSKI.
